GASOLINE CAN OR THE LIKE

Roberto Menghi, Milan, Italy, assignor to Pirelli S.p.A.,
Milan, Italy

Filed July 10, 1959, Ser. No. 56,739

Term of patent 14 years

(Cl. D58—17)

Fig. 1

Fig. 2

Fig. 3

Fig. 4

The side not shown is substantially the same as the side shown.

I claim:

The ornamental design for a gasoline can or the like, substantially as shown and described.
